UNITED STATES PATENT OFFICE.

HOWARD G. ALLEN, OF NIAGARA FALLS, NEW YORK, ASSIGNOR TO THE J. L. MORRISON COMPANY, INC., OF NIAGARA FALLS, NEW YORK, A CORPORATION OF NEW YORK.

RATCHET MECHANISM.

Application filed January 13, 1923. Serial No. 612,511.

To all whom it may concern:

Be it known that I, HOWARD G. ALLEN, a citizen of the United States, residing in Niagara Falls, in the county of Niagara and 5 State of New York, have invented new and useful Improvements in Ratchet Mechanism, of which the following is a specification.

This invention relates to a ratchet mechanism of that type in which the motion is transmitted from the driving member to the driven member by frictional engagement of the rolling clutch members with the driving and driven members.

10 It is the purpose of this invention to provide an improved form of ratchet mechanism of this character which is strong, durable and simple in construction, positive and reliable in its action, and capable of being readily assembled and dismembered for inspection or replacement.

In the accompanying drawings:

Figure 1 is a front elevation, partly broken away, of a ratchet mechanism embodying my improvements. Figure 2 is a longitudinal section taken on line 2—2, Fig. 1. Figure 3 is a fragmentary vertical section taken on line 3—3, Fig. 2. Figure 4 is a front elevation showing a suitable means 20 for operating the ratchet mechanism. Figure 5 is a fragmentary section, on an enlarged scale, taken on line 5—5, Fig. 4.

Similar characters of reference refer to like parts throughout the several views.

25 This ratchet mechanism may be utilized for various purposes, but in this instance the same is shown in connection with the wire feed mechanism of a wire stitching machine which comprises two feed rollers 16, 23, between which the opposing peripheral surfaces of the wire 26 to be fed is gripped and adapted to be advanced at intervals to the mechanism which cuts the wire into suitable lengths for forming staples and driving the same through the parts which are to be stitched together. These feed rollers are secured respectively to gear wheels 18 and 24 by means of rivets 17, which gear wheels intermesh for causing the feed rollers to turn in unison, and are respectively arranged at the rear ends of shafts 11 and

25 which may be journaled for rotation in any suitable bearings on the machine of which they form a part.

One of these shafts, for example, the 55 shaft 11, constitutes the driven shaft to which an intermittent rotary motion is imparted from a suitable source by the ratchet mechanism constructed in accordance with my invention which in its preferred embodiment is constructed as follows:

At its front end the driven shaft 11 is provided with a reduced portion or neck 40 forming a forwardly facing shoulder 41. On this neck is mounted a driven circular 65 spider or hub 2, the periphery of which is provided with one or more recesses 4, preferably six, as shown in Fig. 1, each of which has its bottom 42 inclined circumferentially and at an angle to a radial line from the 70 axis of the spider.

Surrounding this spider or hub is a driving ring or rim 1 which closes the outer sides of the several recesses and forms with each of these a pocket having inner and 75 outer walls which converge forwardly circumferentially of the spider and ring. In each of these pockets is arranged a rolling friction clutch member which in the preferred construction has the form of a roller 80 3 which has a length equal to the width of the spider and ring and such a diameter that its inner and outer sides engage respectively with the inner and outer walls of the respective pocket at a point intermediate the ends 85 thereof when the clutch member is in gripping engagement therewith for coupling the spider and ring. Each of the rolling clutch members 3 is yieldingly pressed toward the small or narrow end of the respective pocket by a spring 5 interposed between the wide end of the pocket and the adjacent side of the clutch member. The clutch members and springs are confined in their respective pockets by means of front and rear retaining plates or disks 6 and 7 arranged on the front and rear sides of the spider and ring so as to cover the sides of the pockets and also prevent lateral displacement of the ring 90 on the spider.

The spider and rear retaining plate are 95 preferably positively interlocked so as to

compel the same to turn in unison with the shaft 8, this being accomplished in the present instance by a key 8 secured to the driven shaft and engaging with notches 29 and 43 in the inner edges of the spider and rear retaining plate.

The rear retaining plate 7 bears against the shoulder 41 of the shaft 11 and the plates 6 and 7 are secured to the spider by 10 screws 27. These plates and the spider are pressed together and the rear plate is pressed against the shoulder 41, by means of a clamping disk 9 engaging the outer side of the front plate 6 and connected with front 15 end of the driven shaft 11 by means of a screw 10.

Upon turning the driving ring forwardly the several clutch members are moved toward the narrow ends of the pockets and 20 grip or wedge between outer and inner walls of the pockets on the ring and spider and thereby cause the same to be coupled and compel them to turn together. Upon turning the driving ring backwardly, the clutch members are moved backwardly toward the wide ends of the pockets sufficiently to release the grip of the clutch members on the ring and spider, thereby permitting the ring to move backwardly independently of the 25 spider. By thus oscillating the ring, an intermittent forward rotary movement of the spider is obtained, the steps as to length being determined by the length of the arc 30 through which the ring is moved back and forth, and thus determines the length of wire which is fed during each cycle of operations of the feed mechanism.

The thickness or width of the ring is 40 slightly less than that of the spider so as to avoid any gripping action of the retaining plates on the ring and permit the latter to turn freely independently of the spider.

The oscillating movement of the ring is 45 preferably effected by means which comprise a rock arm 12 pivotally mounted on the shaft 11 immediately in rear of the rear retaining plate and provided intermediate of its ends with a forwardly projecting pin 13 which engages with a radial groove 14 formed on the rear side of the driving ring. By this means a driving connection is 50 provided between the rock arm 12 and the driving ring which compels these members to turn together yet permits a slight eccentricity in the relative mounting of the ring and arm without liability of cramping the parts.

Various means may be employed for imparting a vibratory motion to the rock arm, those shown in the drawings comprising a 60 rotary crank disk or driving wheel 19 mounted on the driving shaft 30 and provided on its front side with a radial slot 20 which is T-shaped in cross section, a connecting link rod or bar 22 pivotally con-

nected at one end by means of a pin 44 passing through this rod and an opening 15 in the outer end of the rock arm, and an adjusting bolt 21 passing through the rod 22 and having its head arranged in the 70 T-shaped slot and its nut arranged on the front side of the connecting rod.

When the bolt 21 is arranged at the inner end of the slot 20 the same is concentric with the driving disk in which position of 75 the parts no motion would be transmitted from the latter to the feed rollers, but upon adjusting the bolt 21 to different positions in the slot 20 between the axis and periphery of the driving wheel, the length of the 80 feeding action of the roller is varied accordingly.

The manner of mounting the ring on the periphery of the spider not only simplifies the construction and reduces the cost but 85 also results in the production of high class work. A further advantage in transmitting motion from the rock arm to the driving ring is that the ring is free to slide on the spider without liability of binding, inasmuch as the pin 13 merely engages the sides of the groove 14 and is free to slide, and if necessary turn slightly therein in order to 90 adapt itself to the varying positions of the parts. Moreover, this ratchet mechanism 95 as a whole forms a complete unit which is a desirable feature because the same while completely assembled can be placed on a machine instead of necessitating assembling its several parts while the machine itself is 100 being assembled. It is thus possible to quickly remove the entire ratchet mechanism and replace the same by a new one by simply removing the disk or washer 9 and the screw 10.

Obviously balls may be substituted for the 105 rollers 3.

I claim as my invention:

1. A ratchet mechanism comprising a shaft, having a reduced end forming a shoulder, a spider arranged on the reduced part of said shaft and provided in its bore with a notch and in its periphery with a plurality of recesses, each of which has its bottom forming an inner wall which is inclined to a 110 radial line from the axis of said spider, a ring surrounding the periphery of said spider and closing the outer sides of said recesses so as to form therewith pockets each of which has its inner and outer wall converging circumferentially, a plurality of rolling members, one arranged in each of said pockets, front and rear plates mounted on the reduced part of said shaft on opposite sides of 115 said spider, said rear plate being provided with a notch in its inner edge, and a key arranged on said shaft and engaging the notches of said spider and rear plate.

2. A ratchet mechanism comprising a shaft having a reduced end forming a shoul- 120

der, a spider arranged on the reduced part of said shaft and provided in its bore with a notch and in its periphery with a plurality of recesses, each of which has its bottom forming an inner wall which is inclined to a radial line from the axis of said spider, a ring surrounding the periphery of said spider and closing the outer sides of said recesses so as to form therewith pockets, each 10 of which has its inner and outer wall converging circumferentially, a plurality of rolling members, one arranged in each of said pockets, front and rear plates mounted on the reduced part of said shaft on opposite 15 sides of said spider, said rear plate being provided with a notch in its inner edge, a key arranged on said shaft and engaging the notches of said spider and rear plate, and a disk secured to the front end of said 20 shaft and engaging the outer side of said front plate.

3. A ratchet mechanism comprising a shaft having a reduced end forming a shoulder, a spider arranged on the reduced part 25 of said shaft and provided in its bore with a notch and in its periphery with a plurality of recesses each of which has its bottom forming an inner wall which is inclined to a radial line from the axis of said spider, a ring surrounding the periphery of said spider and closing the outer sides of said recesses so as to form therewith pockets, each 30 of which has its inner and outer wall converging circumferentially, a plurality of rolling members, one arranged in each of said pockets, front and rear plates mounted on the reduced part of said shaft on opposite sides of said spider, said rear plate being provided with a notch in its inner edge, a key arranged on said shaft and engaging the notches of said spider and rear plate, a disk secured to the front end of said shaft and engaging the outer side of said front plate, and screws connecting said plates and spider.

4. A ratchet mechanism comprising a shaft, a spider mounted on said shaft and provided in its periphery with a recess, the bottom of which forms an inner wall which is inclined to a radial line from the axis of said spider, a ring surrounding said spider and closing said recess to form a pocket the inner and outer walls of which converge circumferentially, a rolling member arranged in said recess and engaging the inner and outer walls thereof, said ring being provided with a radial groove, and a rocker arm journaled on said shaft and provided with a pin engaging with said groove.

HOWARD G. ALLEN.
